C. W. RICE

AMPLIFYING SYSTEM

Filed Feb. 11, 1919

Inventor:
Chester W. Rice,
by *Alvin G. Davis*
His Attorney.

UNITED STATES PATENT OFFICE.

CHESTER W. RICE, OF SCHENECTADY, NEW YORK, ASSIGNOR TO GENERAL ELECTRIC COMPANY, A CORPORATION OF NEW YORK.

AMPLIFYING SYSTEM.

Application filed February 11, 1919. Serial No. 276,399.

To all whom it may concern:

Be it known that I, CHESTER W. RICE, a citizen of the United States, residing at Schenectady, in the county of Schenectady, State of New York, have invented certain new and useful Improvements in Amplifying Systems, of which the following is a specification.

My present invention relates to the amplification of electric currents of small intensity, and more particularly to the amplification of high frequency currents used for signaling purposes. One of the objects of my invention is to provide an efficient system for amplifying small currents of a particular desired frequency without at the same time amplifying currents of other frequencies to any appreciable extent.

In carrying my invention into effect, I employ a plurality of electron discharge relays or amplifiers, preferably of the high vacuum or pliotron type, and connect these relays in cascade. The plate circuits in all of these amplifiers are supplied with current from a common source and a high resistance is inserted in each plate circuit. The electric current which is to be amplified is applied to the grid circuit of the first amplifier of the series and the current in the plate circuit of that amplifier is varied in accordance with the well known operation of amplifiers of the type mentioned. As a result there will be a variation in the potential difference between the cathode and anode of the amplifier and these potential variations are applied to the grid circuit of the second amplifier. The variable potential between the cathode and anode of the second amplifier is in turn applied to the grid circuit of the third amplifier, and so on throughout the series. The plate circuit of the last amplifier includes a telephone receiver or other device for giving the desired indication of the amplified currents.

In a prior application, Serial No. 183,785, filed July 31, 1917, I have described a system having the general characteristics pointed out above. In obtaining the object of my present invention, I provide what are now commonly known in the art as filtering connections between the successive amplifiers of the series for selecting from the plate circuits potential variations of a certain desired frequency and applying these to the

grid circuits of the succeeding amplifiers in substantially undiminished amplitude while the potential variations of different frequencies occurring in the plate circuits will be applied to the grid circuits in greatly reduced amplitude.

In my prior application above referred to, I have in certain cases applied the potential variations produced in the plate circuits to the grid circuits of the succeeding amplifiers by means of shunt connections between the cathodes and anodes of the amplifiers, which shunt connections comprise a resistance in series with a capacity, the potential variation across the resistance being the operating potential which is applied to the grid circuit of the succeeding amplifier. A connection of this kind is useful for accomplishing the purposes of the present invention in that the condenser offers a high impedance to low frequency currents and a low impedance to high frequency currents. As a result the greater percentage of the drop of potential in the circuit produced by high frequency currents occurs across the resistance, and it is therefore effective upon the grid of the succeeding amplifier. For low frequency currents, however, the greater proportion of the drop in potential occurs across the condenser, and this drop in potential has no effect upon the grid circuit of the succeeding amplifier.

I have also in one case in the above mentioned application shown a modification in which the shunt circuit mentioned is made up of a condenser in series with a combination of inductance and capacity in parallel, which is resonant to the frequency of the currents which it is desired to amplify. This combination is more effective as a wave filter because of the fact that the capacity and inductance in parallel offer an extremely high impedance to currents of one particular frequency and a much lower impedance to every other frequency either higher or lower than the desired frequency.

In my application mentioned above, I have claimed specifically the connection in which the shunt circuit is made up of capacity and resistance, but I have not claimed broadly the use of a wave filtering connection between the successive amplifiers.

My present invention will best be understood by reference to the following descrip-

tion taken in connection with the accompanying drawing which shows a diagrammatic representation of circuit connections which may be employed in carrying my invention into effect.

As indicated in the drawing, an antenna 1 is connected by means of the usual inductive coupling 2 to the grid circuit of the amplifier 3. The plate circuit of this amplifier, as well as the plate circuits of amplifiers 4, 5 and 6, is supplied with current from the battery 7. By means of a tap from this battery at 8 the filamentary cathodes of the amplifiers are supplied with heating current at the proper voltage, variable resistances 9, 10, 11, and 12, in series with the different cathodes allowing for the adjustment of the temperature of each cathode independently of the others. In the plate circuits of amplifiers 3, 4, 5 and 6, I insert high resistances 13, 14, 15 and 16. When current is received in the antenna the potential of the grid of amplifier 3 is varied and the current through the amplifier is varied accordingly. As a result the potential of the anode of the amplifier varies with respect to the cathode. In order to impress this potential variation upon the grid circuit of amplifier 4, a shunt circuit is provided between the cathode and anode of amplifier 3, which comprises a condenser 17 in series with a variable condenser 18 and an inductance 19 in parallel. The grid of amplifier 4 is connected to a point between the condenser 17 and the condenser 18 and inductance 19. As a result the potential variations across the combination of condenser 18 and inductance 19 are effective in the grid circuit of amplifier 4. The condenser 17 offers a comparatively low impedance to the high frequency currents while the combination of condenser 18 and inductance 19 offers a very high impedance to currents of the frequency for which this combination is resonant. If, therefore, this combination is tuned to the frequency of the currents which it is desired to amplify, the greater portion of the potential drop in the shunt circuit for currents of the desired frequency will be effective upon the grid circuit of amplifier 4. Condenser 17 offers a very high impedance to low frequency currents and hence the greater proportion of the potential drop for low frequency currents through the shunt circuit will occur across the terminals of condenser 17, and these low frequency potential variations will be impressed upon the grid circuit of amplifier 4 in greatly reduced amplitude. The combination of condenser 18 and inductance 19 offers a much lower impedance to currents of greater frequency than to currents of the desired frequency, and therefore the amplitude of potential variations of higher frequency with respect to those of the desired fre-

quency will also be greatly reduced in the grid circuit of amplifier 4.

Thus it will appear that the arrangement which I have shown is highly selective to potential variations of the desired frequency and permits the amplification of these potential variations without producing any great amplification of potential variations of other frequencies. This arrangement is of particular value where it is desired to secure a high amplification of a particular high frequency without at the same time amplifying currents of other frequencies which may be impressed upon the system or which may be produced therein by reason of the action of the apparatus. The resulting potential variations between the cathode and anode of amplifier 4 are impressed upon the grid circuit of amplifier 5 in the same manner as that which has just been described by means of a similar shunt circuit made up of condenser 20 and variable condenser 21 and inductance 22 in parallel. The potential variations set up between the cathode and anode of amplifier 5 are in turn impressed upon the grid circuit of amplifier 6 in the same manner.

While I have indicated only four amplifiers thus connected in cascade, as many amplifiers as desired or as may be necessary to secure the desired degree of amplification may be thus connected. In the present case the variable potential between the cathode and anode of amplifier 6 is applied by means of a condenser 23 to the telephone receiver 24, in order to render the received signals audible. In case the signals to be received are transmitted by means of continuous waves local oscillations for receiving by the heterodyne method may be produced by the electron discharge generator 25, connected as shown, so as to impress local oscillations upon the circuit which includes the telephone receiver 24.

While I have shown and described a filtering connection made up of a condenser in series with an inductance and capacity in parallel, my invention is not limited to this particular connection as in my claims which call broadly for a filtering connection I mean to include a connection of the type described in my prior application which is made up of a condenser with a high resistance in series therewith. It will be apparent also that my broad claims are not limited to the use of either one of these connections to the exclusion of the other as both forms of connection may be employed in the same amplifying system. It is also apparent that many other modifications in the particular connections used and in the specific use to which my invention is applied may be made without departing from the scope of my invention as set forth in the appended claims.

What I claim as new and desire to secure by Letters Patent of the United States, is:—

1. The combination in an amplifying system of a plurality of electron discharge amplifiers each of which has a cathode, an anode and a grid and plate and grid circuits, means for impressing currents which are to be amplified upon the grid circuit of one of said amplifiers, high ohmic resistances in the plate circuits of said amplifiers, a connection from the anode of said first amplifier to the grid of a second amplifier, said connection including a condenser and a connection between the cathode and grid of the second amplifier which is resonant to the frequency of the currents to be amplified, the last mentioned connections in series with the condenser forming a shunt circuit between the cathode and anode of the first amplifier.
2. The combination in an amplifying system of a plurality of electron discharge amplifiers connected in cascade, each of which has a cathode, an anode and a grid, and plate and grid circuits, means for impressing currents which are to be amplified upon the grid circuit of one of said amplifiers, shunt circuits connecting the anodes and cathodes of each amplifier of the series except the last, a portion of each of said shunt circuits having a low impedance for currents of the frequency to be amplified, another portion of each of said shunt circuits having a high impedance for currents of the frequency to be amplified, and a much lower impedance for currents of lower frequencies, and means for impressing the potential variations set up across this portion of the shunt circuit upon the grid circuit of the next succeeding amplifier of the series.
3. The combination in an amplifying system of a series of electron discharge amplifiers, each of which has a cathode, an anode, and a grid and plate and grid circuits, means for impressing currents to be amplified upon the grid circuit of one of said amplifiers, high ohmic resistances in the plate circuits of said amplifiers, connections from each of the anodes of said amplifiers except the last of the series to the grid of the next succeeding amplifier, each of said connections including a condenser and a connection between the cathode and grid of each of said amplifiers which is resonant to the frequency of the currents to be amplified said last mentioned connections in series with the condensers forming shunt circuits between the cathodes and anodes of the amplifiers.
4. The combination in an amplifying system of a plurality of electron discharge amplifiers connected in cascade, each of which has a cathode, an anode and a grid, and plate and grid circuits means for impressing currents which are to be amplified upon the grid circuit of one of said amplifiers, shunt circuits connecting the anodes and cathodes of each amplifier of the series except the last, a portion of each of said shunt circuits having a low impedance for currents of the frequency to be amplified, another portion of each of said shunt circuits having a high impedance for currents of the frequency to be amplified, and a much lower impedance for currents of other frequencies, and means for impressing the potential variations set up across this portion of the shunt circuit upon the grid circuit of the next succeeding amplifier of the series.
5. The combination in an amplifying system of a series of electron discharge amplifiers each of which has a cathode, an anode, and a grid, and plate and grid circuits, means for impressing currents which are to be amplified upon the grid circuit of the first of said amplifiers, shunt circuits connecting the anodes and cathodes of each amplifier of the series except the last, each of said shunt circuits comprising a condenser in series with a parallel circuit which is resonant to the frequency of the currents to be amplified, said resonant circuit being connected to the grid circuit of the next succeeding amplifier of the series.
6. The combination in a radio receiving system of a plurality of electron discharge amplifiers connected in cascade, each of which has a cathode, an anode and a grid, and plate and grid circuits, means for impressing received impulses upon the grid circuit of the first, a detector having a local source of high frequency oscillations associated therewith operatively related to the plate circuit of the last amplifier of the series, shunt circuits connecting the anodes and cathodes of each amplifier of the series, except the last, a portion of each of said shunt circuits having a high impedance for currents of the frequency to be amplified and a much lower impedance for currents of other frequencies, and means for impressing the potential variations set up across this portion of the shunt circuit upon the grid circuit of the next succeeding amplifier of the series.
7. The combination in an amplifying system of a plurality of electron discharge amplifiers each of which has a cathode, an anode and a grid, and plate and grid circuits, means for impressing currents which are to be amplified upon the grid circuit of one of said amplifiers, high impedances in the plate circuits of said amplifiers, a direct connection through a condenser from the anode of the first amplifier to the grid of the second amplifier, and a parallel resonant circuit connecting the cathode and grid of the second amplifier, said resonant circuit being tuned to the frequency of the currents to be amplified and forming in connection with the condenser a shunt circuit between the cathode and anode of the first amplifier.

4

8. The combination in an amplifying system of a series of electron discharge amplifiers each of which has a cathode, an anode and a grid, and plate and grid circuits, 5 means for impressing currents to be amplified upon the grid circuit of one of said amplifiers, high impedance in the plate circuits of said amplifiers, connections from each of the anodes of the amplifiers except the last 10 of the series to the grid of the next succeeding amplifier, each of said connections including a condenser, a parallel resonant circuit con-

nected between the cathode and grid of each of said amplifiers which is tuned to the frequency of the currents to be amplified said resonant circuits forming in connection with the condensers shunt circuits between the cathodes and anodes of the amplifiers, and a common connection between the cathodes of all of the amplifiers.

15 In witness whereof, I have hereunto set my hand this 10th day of February, 1919.

20 CHESTER W. RICE.
